UNITED STATES PATENT OFFICE.

MARION MELLEN, NOW BY MARRIAGE MARION MELLEN LITTLE, OF NEW YORK, N. Y.

GAME-TABLE SURFACE.

Application filed May 2, 1924. Serial No. 710,561.

This invention is a game table surface for use in playing a game of Chinese origin using tiles marked as "flowers," "winds," "dragons," "seasons," etc., variously known 5 as "Mah jongg," "Prung chow," etc.

The table cover or table top, according to this invention, is provided with indicia showing the score count, and the doubling score, so that the number of points made by a 10 player at the end of the hand may be very readily and quickly computed.

More specifically, the table cover, or table top has the doubling score marked directly on it in any suitable way, one of these doubling scores being positioned in front of each 15 of the four players.

There is also marked on the table cover the score count, one of these score counts each 20 being likewise marked on the table cover in front of each of the four players.

With the score count and doubling scores thus continually before him, a player can readily and quickly decide what combinations it would be best for him to concentrate 25 on and what tiles to get rid of. This feature is particularly valuable to a beginner to whom the scoring in this game is sometimes rather bewildering. The markings on the cover are therefore useful during the 30 playing of the hand, as well as at the end of the hand, in computing the score.

The table cover top is also provided preferably with markings indicating the position or placement of the wall.

In a modified form, the invention also 35 comprises means whereby the score count and doubling score may be covered up or removed, so that the table cover or table top may be used for some other game.

With a table cover thus marked, so that the score count or doubling score are always before each player, there is no necessity for referring to a book showing such score count or doubling score, or for looking on the 45 bottom of the racks where such indicia are sometimes placed.

The general features of the invention having thus been outlined, certain embodiments thereof are illustrated in the accompanying 50 drawings, in which

Fig. 1 is a plan view of a preferred form of the invention:

Fig. 2 is an enlarged view of the score count and the doubling score:

55 Figs. 3 and 4 show two modifications. Referring now to these drawings in which

similar reference characters indicate similar parts, the table cover made preferably of fabric material 1 is cut away at the corners, and provided with tapes 2 having weighted 60 tips 2^a and an adjusting ring 2^b. The cover may be secured to table tops of different sizes by means of the tapes 2 and adjusting ring 2^b.

In order to indicate the location or placement of the wall there are provided lines 3, in form of a centrally placed square or rectangle, which lines may be used to mark the inner or outer edge of the wall.

In front of each player there is marked 70 a doubling score 4, and also in front of each player there is marked the score count 5. The particular indicia in the doubling score and the score count are well known in the game, and the details thereof need not be 75 repeated here.

These markings 4 and 5 are preferably placed on the table cover in such a position that when racks are used to hold the tiles the indicia of the doubling score and the score 80 count are visible.

Fig. 3 shows a modification where a strip 6 may be detachably secured to the table top or cover 1 for covering up the doubling score and score count, when it is desired to 85 use the table cover for some other game such as bridge. Fastening elements 7 on the strip 6 cooperate with corresponding fastening elements 8 on the cover 1 for detachably securing the strip in place. Fastening elements 90 7 and 8 may be of the well known ball and socket type, elements 8 preferably being the sockets.

Fig. 4 shows another modification where the doubling score 10 and score counts 11 95 are marked on a strip of material 13 which is adapted to be detachably secured to the table top 1 by fastening elements 12 which cooperate with the elements on the cover 1 similar to those shown at 8, Fig. 3. With 100 this modification, when it is desired to play some other game such as bridge, the strip 13 is simply removed.

These table covers, are to be manufactured in any color and bound with tape, ribbon or 105 other materials as desired.

While I have illustrated a preferred form of the invention, in some detail, it should be understood that the invention is not limited to the details shown, but may be carried 110 out in other ways as expressed in the scope of the following claims.

I claim as my invention:—

1. As an article of manufacture, a table cover of fabric material, a strip of fabric material adapted to be detachably secured to the table cover, one of the pieces of fabric material being provided with indicia thereon for use in computing the score in a game of the character described, whereby the said indicia will be visible or not, dependent upon the relative placement of one fabric material with respect to the other.

2. An article of manufacture comprising a table cover consisting of two members, one of which is adapted to be secured to a table top, the other being detachably secured thereto, indicia on one of the members being exposed or hidden according to the relative positioning of the members, said detachable member being attachable to the other member so as to be quickly removable by a single movement of the hand.

3. An article of manufacture comprising

two members consisting of a table cover, a strip of material, snap fasteners on said members for detachably securing them together, indicia on one of said members for aiding in playing a game, and adapted to be concealed or exposed according to the relative positioning of the members, said strip of material being of a size and shape to exactly cover the sight of the indicia.

4. An article of manufacture comprising a table cover of flexible material, means for securing said cover to the table in position to cover the top thereof, indicia on said cover for aiding in the playing of a game, a strip of material of a suitable size and shape to cover said indicia, and snap fasteners for detachably connecting the strip to the table cover.

In testimony whereof I affix my signature,

MARION MELLEN.
